CLAIM

The ornamental design for a cover for wall mounted electronic equipment, as shown and described.

DESCRIPTION

FIG. 1 is a top plan view of the cover for wall mounted electronic equipment showing our new design;

FIG. 2 is a left side elevational view, the right side being a mirror image thereof;

FIG. 3 is a front elevational view thereof;

FIG. 4 is a bottom plan view thereof;

FIG. 5 is a rear elevational view thereof; and,

FIG. 6 is a front left side perspective view thereof.

FIG. 1

FIG. 2

FIG. 3

FIG. 4

FIG. 5

FIG. 6
